UNITED STATES PATENT OFFICE.

JAMES REID, OF WATERTOWN, AND ALBERT M. LEAHY, OF SOMERVILLE, MASSACHUSETTS.

DETACHABLE CHAIN-LINK.

1,386,732.

Specification of Letters Patent. Patented Aug. 9, 1921.

Application filed October 13, 1920. Serial No. 416,748.

To all whom it may concern:

Be it known that we, JAMES REID, a citizen of the United States, residing at Watertown, in the county of Middlesex and Commonwealth of Massachusetts, and ALBERT M. LEAHY, a citizen of the United States, residing at Somerville, in the county of Middlesex and Commonwealth of Massachusetts, have invented a new and useful 10 Improvement in Detachable Chain-Links, of which the following, together with the accompanying drawings, is a specification.

The objects of our present invention are to produce a chain link capable of being detached from its associated links in a chain or cable and especially adapted for use in ship cables; to enable the link to be forged from a high grade or alloy steel, thereby securing greater tensile strength and to allow any defective or broken links to be easily disconnected and repaired, and these objects, among others, are secured, by the construction hereinafter described and illustrated in the accompanying drawings, in which Figure 1 represents in side elevation one of our improved detachable links.

Fig. 2 represents an edge view of the same.

Fig. 3 is an end view of one of the detachable or coupling members removed from the link.

Fig. 4 is a side view of the same.

Fig. 5 represents a side view of the link with the detachable or coupling members removed.

Fig. 6 represents one of our detachable links associated with two additional links, and illustrating the manner of forming a cable.

Fig. 7 is a detached view of the pin for uniting the detachable or coupling members.

Fig. 8 is a detached view of the keying ring for holding the pin in position.

Fig. 9 represents a detachable chain link having the central stud of the coupling members removed.

Fig. 10 is a transverse central sectional view of the link as shown in Fig. 1, and

Fig. 11 is a transverse central sectional view of the link as shown in Fig. 9.

Similar reference characters refer to similar parts in the different figures.

According to the present practice of forming ship cables, each individual link is provided with an open end having a scarf joint

to enable an associated link to be engaged. The scarf joint at the end of the link is subsequently welded. This method of forming the links of ship cables necessitates the use of a metal capable of being welded, and for this purpose wrought iron is commonly used, requiring frequent tests in order to detect any defective links. The cables are constructed in separate sections termed "shots", of varying lengths. Whenever a defective link is detected the entire section is transferred to the repair shop. The sections are united by shackles to form a continuous cable. The use of shackles for uniting the sections of the cables is liable to interfere with the movement of the cable over the windlass or through the hawse-pipe.

By means of our present invention all the links of the cable can be forged from an alloy steel, thereby securing greater tensile strength and reducing the liability of abrasion or corrosion, producing a cable of uniform links capable of being separated for repairing, thereby avoiding the transportation of an entire section or "shot", or the use of shackles, and reducing the liability of fouling of the cable. To carry our invention into effect, we form a cable having alternate detachable links, as illustrated in the accompanying drawings and hereinafter described. The detachable link forming the subject of our present invention is represented in side view in Fig. 1 and in edge view in Fig. 2.

The link as originally forged from an alloy steel is represented in Fig. 5 having a C-shape, provided with ends 1, 1, with an open space 2 between them. Each of the ends 1, 1, is provided with cylindrical projections 3, 3, provided at their ends with enlarged flanges 4, 4, forming shoulders 5, 5. The ends 1, 1, are slightly beveled at 6, 6. In case the link is to be provided with a central stud we form a boss 7 on the side of the link opposite the open space 2 in the end of which we form a V-shaped notch 8. Each of the forged C-shaped links, as shown in Fig. 5, is capable of being used as a hook for cranes or davit falls, but when used as a cable the open space 2 is closed by 105 duplicate coupling members 9, 9, one of which is shown detached in Figs. 3 and 4. The coupling members 9, 9, are likewise forged from an alloy steel having their opposing surfaces 10, 10, plain, and having 110

- forged recesses 3^a and 4^a fitting the projections 3 and flanges 4. The coupling members 9, 9, are also provided with projections 11, 11, having beveled ends 12, 12, fitting the 5 V-shaped notch 8. When the coupling members 9, 9, are placed in position they securely unite the ends 1, 1, of the C-shaped forged link, the projection 11, forming a central stud between the openings 13, 13.
- 10 When the coupling members 9, 9, have been placed in position with their plane sides opposing each other, and inclosing the projections 3 and flanges 4, they are united by a tapered pin 14 having at its smaller end 15 an annular recess 15 to receive a lead keying ring 16 which is swaged into the recess 15, thereby holding the pin 14 in position. The pin 14 is substantially like the forelock pin now used to unite the parts of shackles. In 20 place of the pins 14, as represented in Fig. 2, the coupling members may be united by means of a screw 17, Fig. 6, screw threaded into one of the members and having a countersunk head, or any convenient and suitable method may be employed for holding 25 the plain surfaces 10, 10, of the coupling members in contact. When the pin 14 is employed to unite the duplicate coupling members, it is preferably placed at an oblique 30 angle to the plane surfaces 10, 10 of the coupling members in order to resist the strain incident to the lateral movement of the coupling members in withdrawing them from the C shaped link.
- 35 In case it is preferred to prepare the detachable links without a central stud, the projection 11 and the boss 7 can be omitted and the C-shaped link, when assembled, will present a single opening, as shown in Fig. 9.
- 40 The coupling members when the projection 11 is omitted will consist of two semi-cylindrical pieces 9^a, as shown in sectional view in Fig. 11, each coupling member being recessed to receive the cylindrical projections 45 3 and flanges 4, 4, as represented by broken lines in Fig. 9. By removing the coupling members 9, 9, links 19 and 20 may be hooked into the detachable link, as shown in Fig. 6, said links 19 and 20 may also be forged from 50 an alloy steel and may either be provided with central studs or the latter may be omitted. If the alternate links of the cable are detachable it will be possible to separate the individual links of the cable whenever it may 55 be necessary to repair a link. All the links of the cable are capable of being forged whether solid or detachable, and if made of an alloy steel and subsequently subjected to a well known heat treatment the tensile 60 strength of the cable may be materially increased or, if desired, the weight of the cable can be decreased. We are aware that it has been proposed to construct a detachable link having a C-shaped member provided with an 65 open side, closed to complete the link, and we

do not claim such broadly. The object of our present invention is to simplify the construction and reduce the cost and to provide a method of forming a detachable link which can be used either with or without a central stud. 70

We claim,

1. A detachable chain or cable link, comprising a C-shaped member having an open side with cylindrical flanged projections at 75 its ends, a pair of duplicate coupling members for closing the open side of said C-shaped member, each of said coupling members having recesses for the reception of said projections, and plain abutting sides held 80 in contact in the plane of said C-shaped member, and means for uniting said coupling members.

2. In a detachable chain or cable link, the combination with a C-shaped member having cylindrical flanged projections at its ends, of a pair of coupling members provided with recesses for said flanged projections, with said coupling members applied to the opposite lateral sides of said flanged projections, and means for uniting said coupling members passing between the ends of said flanged projections. 85 90

3. In a detachable chain or cable link, the combination with a C-shaped member having an open side provided with flanged cylindrical projections at its ends, of a pair of coupling members for closing said open side, having plain abutting sides diametrical to 95 said cylindrical projections, and means for 100 uniting said coupling members.

4. In a detachable chain or cable link, the combination with a C-shaped member having flanged cylindrical projections at its ends, of a pair of coupling members provided with recesses to receive said flanged projections, each of said coupling members having projections extending across the link to form a central stud, and means for uniting 105 said coupling members between the 110 flanged projections of the C-shaped member.

5. In a detachable chain or cable link, the combination with a C-shaped member having flanged cylindrical projections at its ends, of a pair of duplicate coupling members having semi-cylindrical recesses engaging the opposite sides of said flanged projections, with plain abutting surfaces in the plane of said C-shaped member, and means for uniting said coupling members between 115 the ends of said cylindrical flanged projections. 120

6. The combination in a detachable link for a chain or cable, of a C-shaped link having an opening on one of its sides, a projection upon its side opposite said opening provided with an interior V-shaped notch, a pair of coupling members for closing the opening in said link, said coupling members having recesses for engaging the ends of the 125 130

5 **C**-shaped link on opposite sides of said opening to resist a tensile strain upon the **C**-shaped link, means for uniting the coupling members, and projections on said coupling members provided with beveled ends fitting said V-shaped notch and forming a stud dividing link into two parts.

7. The combination in a detachable link for a chain or cable, of a **C**-shaped member, 10 means for closing the open side of the **C**-shaped member and engaging its ends on opposite sides of said opening to resist the tensile strain upon said **C**-shaped member, consisting of a pair of coupling members, 15 and a pin for uniting said coupling members, said pin passing obliquely through said coupling members.

8. As an article of manufacture, a detachable link for a chain or cable, comprising

20 **C**-shaped member having an open side and flanged cylindrical projections at its ends and a pair of identical coupling members recessed to receive said projections, and means for uniting said coupling members between said flanged projections.

25 9. As an article of manufacture, a detachable link for a chain or cable, comprising a **C**-shaped member having an open side and provided with projections at its ends, and a pair of duplicate coupling members recessed to receive said projections and resist a tensile strain on said **C**-shaped member, and means for uniting said coupling members.

Dated this fifth day of October, 1920.

JAMES REID.
ALBERT M. LEAHY.
